UNITED STATES PATENT OFFICE.

JAMES BALLARD MOORE AND GEORGE DOMINIC GALLAGHER, OF WASHINGTON,
DISTRICT OF COLUMBIA.

COIN-CONTROLLED CLOCK BANK.

Application filed February 24, 1922. Serial No. 538,908.

To all whom it may concern:

Be it known that we, JAMES BALLARD MOORE and GEORGE DOMINIC GALLAGHER, citizens of the United States, residing at 5 Washington, D. C., have invented certain new and useful Improvements in Coin-Controlled Clock Banks, of which the following is a description, reference being had to the accompanying drawing and to the figures of 10 reference marked thereon.

This invention relates to a money box or savings bank and more particularly to a savings bank having a time piece therein constructed and arranged to be wound on the 15 insertion of a coin.

Heretofore it has been proposed to rigidly mount a time piece in a bank and to either normally lock the winding arbor of the time piece from being wound by coin controlled 20 locking mechanism; or it has been proposed to prevent the winding arbor from being wound by masking it with a movable shutter or guard so as to normally render the winding arbor inaccessible for winding.

25 These guards in such instances have been locked from releasing movement but have been arranged to be released by the insertion of a coin, thereby rendering the winding arbor accessible for winding the time

30 piece. Such prior constructions have been in a manner objectionable because of their complicated and expensive coin controlled mechanism and because of the general ornate appearance of projecting operating 35 parts such as the movable guard and the actuating plunger for operating the guard or the coin control mechanism.

One of the objects of this invention is to 40 provide a coin-controlled time piece savings bank embodying either of the before mentioned types which will be strikingly simple, ornamental and effective.

Another object of the present invention is to 45 provide a bank substantially freed of the more or less unsightly projecting plungers and control mechanism, wherein the operation is effected by shiftably mounting the time piece in the bank, in coin controlling the shifting movement, and in utilizing the 50 shifting movement to permit the winding of the time piece. This broad aspect of the invention comprehends either, a construction wherein the winding arbor is normally

positively locked against winding movement or is normally inaccessible for winding. And 55 it further embraces either a construction wherein the winding arbor itself is used as a means for shifting the time piece or a construction wherein a plunger, coin, lever or other means is utilized for shifting the time 60 piece.

Still another feature of the present invention resides in the utilization of a specific shifting movement of the time piece, namely, 65 an oscillatory movement, wherein the time piece has its winding arbor normally inoperative for winding but which, on oscillation of the time piece is rendered operable for winding.

An additional phase of the invention resides in so oscillatably mounting the time piece in the bank with the dial thereof appearing through a corresponding dial aperture in the bank, that on oscillation of the time piece from normal non-winding to temporary winding position the time piece dial, while maintaining a perfect fit in the dial aperture of the bank will oscillate relatively thereto so as to render the face of the time piece inconveniently positioned to be easily 80 readable if left in winding position thereby preventing misuse of the device.

Yet another feature of the invention resides in utilizing the enclosing walls of the bank itself as a direct means for preventing 85 the winding shaft of the time piece from being wound. And this adaptation of the invention includes not only constructions for positively locking the winding arbor from movement but also constructions preventing 90 normal access to the winding arbor.

Still a further object of the invention resides in providing a bank inclosing a time piece having an ever accessible winding arbor normally incapable of being wound but 95 releasable for winding on the insertion of a coin. This broad feature of the invention embraces either a construction wherein the time piece is shiftable to effect the release or a stationary time piece construction 100 wherein some locking mechanism is shiftable to effect the release.

A further important feature of this invention resides in providing an attachment for a standard stem wound time piece, such 105 as a clock or watch, embodying a preferably

detachable, auxiliary winding head constructed and arranged to cooperate with some type of means for normally preventing the winding of said head yet permitting its winding on the insertion of a coin.

Other ancillary objects of the invention include the facile removability of the time piece from the bank for replacement, the specific type of locking mechanism, the specific coin control mechanism, the specific means for preventing the recovery of the coin after insertion, the means for insuring the return oscillation of the time piece after its initial movement to winding position, 15 the novel cradle for the time piece, and its mounting in the bank casing and other specific and broad details of construction not herein particularly recited.

These and other objects will be apparent 20 from a perusal of the following specification when taken in connection with the accompanying drawings which illustrate the preferred embodiment of one form of the invention. Referring now to the drawings,

25 Figure 1 represents a front view of one form of the invention, certain parts being broken away.

Figure 2 is a plan view thereof, the top of the casing being broken away.

30 Figure 3 is a side elevation with a part of the casing broken away.

Figure 4 is a front elevation showing the front extension of the bank casing.

Figure 5 is a plan view thereof.

35 Figure 6 is a plan view of the partition and coin chute.

Figure 7 is a front elevation thereof.

Figure 8 is a plan view of the spring locking finger.

40 Figure 9 is a side elevation thereof.

Figure 10 is a plan view of the coin slide.

Figure 11 is a front view thereof.

Figure 12 is a rear view of the cradle for the time piece.

45 Figure 13 is a side view thereof.

Figure 14 is a plan and side view, the latter in section of the slotted sleeve for gripping the winding head of the time piece.

50 Figure 15 is a plan and side view of the auxiliary winding head.

Referring now to that form of the invention which has been illustrated in the drawings as being one embodiment of the invention—it being manifest that such construction is merely illustrative and in no sense limitative, the bank or coin receptacle proper comprises an enclosing casing 1 of any pleasing shape and size, preferably of sheet metal, having its front face 2 suitably apertured as at 3 to form an opening for the face or dial of the time piece 4. At the outset it is to be understood that the word time piece is used generically to designate a stem winding watch or clock or a 60 clock having winding and setting controls at

the rear or a stem winding clock or watch provided with certain attachments to the winding stem as hereinafter described, or a clock having suitable modified winding and setting controls at the rear. In fact the 70 invention contemplates the utilization of any type of standard clock or watch as well as clocks or watches specially modified.

The casing 1 is closed at the base or at the rear if desired by means of a door 5 preferably swingingly mounted on the pivot 6. Any type of lock may be used for the door. Obviously the base or rear of the casing may be provided with the usual additional coin and paper money openings, not shown.

80 The time piece 4 is mounted in the casing so as to have movement relative to said casing and in the preferred form of the invention this movement of the time piece is utilized as a means for permitting the time piece to be wound. In the broad aspect of the invention the shifting movement of the time piece relative to the casing may be of any nature—including a bodily shifting therein, but preferably the time piece is 85 mounted to oscillate about an axis about which the hands of the time piece revolve.

90 To this end, the time piece which in the present instance is illustrated as a stem wound watch or clock is carried in a circular cup-shaped cradle 7, see Figures 12 and 13. This cradle is cut away or notched as at 8 to permit the winding stem 9 to pass therethrough and the rear of the cradle is provided with a punched out tit 10. The circular aperture 3 in the front wall of the casing is dished-in somewhat at this opening as at 11. The time piece carried in its cradle 7 is mounted in this opening 3 in such a manner that the inner wall of the dished-in opening resiliently and firmly grips the face of the time piece to provide a circular bearing at this point. It will also be noticed that the front circular wall 12 of the cradle 7 engages behind the circular dished-in portion 11 of the casing thereby forming a 100 good circular bearing at this point also. The time piece is held in such position by means of a U-shaped sheet metal keeper 13 formed with a central perforation 14 through 105 which the tit 10 on the rear face of the cradle centers. In this manner the resiliency of the legs of the keeper pressing against the rear wall of the casing 1 and the apertured portion 14 of the keeper 13 pressing around the tit 10 of the cradle, firmly hold the time piece and cradle in position at the same time providing a good bearing both at front and rear, so that the time piece can be easily revolved or oscillated about an axis passing through the axis of its hands. The above construction permits a ready assembly 115 and disassembly of the time piece. When it is desired to remove it the keeper is first pulled downwardly by forcing it over the

tit and then the time piece may be removed as will hereinafter be evident. Manifestly various other means may be utilized for removably mounting the time piece in the 5 casing including variant types and designs of cradles adaptable to the divers styles of time pieces and other designs of keepers and cradle mountings.

The present invention contemplates various 10 constructions for utilizing the shifting movement of the time piece relative to the casing in order to permit the time piece to be wound. The present illustrated design is but an example. For instance one aspect of 15 the invention also embraces means for positively locking the winding arbor of the time piece from rotation. A very convenient construction is disclosed in the drawings, wherein the usual winding head of the clock 20 or watch is provided with an extension in the nature of an auxiliary winding head or key 15, which may be that of the standard stem wound clock or watch and is applied as a rigid extension of the usual winding 25 head or key of the watch or clock. Obviously the invention includes any type of auxiliary winding attachment to any standard or modified time piece as hereinbefore explained. As shown clearly in Figures 1, 30 14 and 15, the usual stem 9 is surrounded with a sleeve 16, slotted as at 17. This sleeve is threaded at its upper exterior to engage interior threads on a surrounding cap 18 provided with an upstanding square 35 collar 19. This collar is broached or provided with a square aperture or key-way 20 into which snugly fits the squared end or key 21 of the auxiliary separable winding head 22. Just above the squared end 21, 40 this winding key is formed round as at 23 and this round portion 23 is of the same diameter as a side of the square collar 19. Immediately above the round portion 23, the winding head 22 is formed with a flange 45 24 which serves to hold the winding head in place in the casing. Obviously the winding head is of two part construction so as to permit its assembly in the casing. As is evident the neck of this winding head 22 50 passes snugly through an elongated slot 25 in the top of the casing 1. From the above described construction, it will be seen that when the cap 19 is threaded down upon the split sleeve 18, the latter is made to firmly 55 grip the knurled head 15 of the time piece. If desired a spacing two-piece washer 26 is placed around the stem 9. This washer is nothing more than an ordinary circular washer divided diametrically so that it can 60 be detachably positioned around the winding stem 9. When it is desired to remove the time piece it is pulled out taking with it the sleeve 18 and cap 19, the separation taking place between the square key 21 and 65 the key way 20. The auxiliary winding head 22 remains fixed in the casing 1. The angularly shaped locking portion or key-way 20 of the collar 19 is formed of requisite length so that on depression of the head 22 for the usual hand setting operation, this 70 square portion 20 will sink below the level of the locking slot 28 of the locking spring 26 which is shown in its normally lowermost position, and the round portion 23 will pass into the slot 28 thereby permitting the setting of the watch. It is obvious that during this setting operation, the winding mechanism is thrown out of operation by the longitudinal shifting of the winding arbor as in all stem-wound, stem-set time 75 pieces. It will be seen that with such a construction, the watch may be set at any time independently of the coin-controlled mechanism for preventing the winding of the arbor. 80

Means is provided for preventing the winding arbor of the time piece from being wound. While in certain embodiments of this invention this may be accomplished by rendering the winding arbor inaccessible, 85 as hereinafter described, the present drawings illustrate means for positively holding the winding shaft from rotation. One form of this positive means is illustrated as a resilient locking spring 26, see Figures 8 90 and 9, having one end thereof riveted as at 27 to the side wall of the casing. This spring is formed at its other end with a locking slot 28. There is also provided a lateral coin toe 29. The locking slot 28 is 95 shaped to snugly fit the square portion 19 of the auxiliary winding head and in such normal lowered position prevents the winding shaft from being turned. By this construction if the spring 26 is slightly 100 raised the locking slot will surround the upper round portion 23 of the auxiliary head 22, to permit the winding shaft to be wound. The length of the slot permits the 105 oscillation of the time piece. 110

Any desired coin operated means for operating this locking spring 26 may be availed of. In the present instance a coin finger 29 is arranged to oscillate with the time piece so as to carry a coin, by the oscillation of the time piece into contact with the lateral locking toe to cause the locking strip 26 to be raised or moved at the proper time to free the winding stem for winding 115 rotation. In the present construction it is preferred to rivet the coin finger 29 to a slide 30 herein shown as curved to conform to the curved top of the casing 1. This slide is provided with a hole or notch 31 through which the winding stem of the auxiliary head 22 passes so that oscillation of the time piece also oscillates the coin tongue. In addition the slide 30 is provided with the extensions 32 and 33 which cover the slot 25 and the coin slot 34 in 120 125 130

the top of the casing. As a means for guiding this slide in its reciprocations and holding it in place the slide is provided at any convenient point with an elongated slot 35 through which loosely passes a rivet 36 in the top of the casing. Obviously these details of construction are subject to change in design.

As indicated clearly in Figures 3 and 10, 10 the coin finger 29 is arranged at the rear of the time piece, altho not necessarily so, and is adapted to normally rest under the coin slot 34 so that a dime or other coin when inserted will rest on this finger. The coin is 15 guided laterally by a coin guide or raceway which in the present instance is formed by a partition member 37 most clearly shown in detail in Figures 6 and 7. This partition 37 is of sheet metal bent to the desired form 20 and riveted to the side of the casing as at 38 and 39. This partition forms the rear face of the coin guide. The front face is preferably formed by a separate spaced sheet metal member 40 riveted as at 41 and 25 42 to the partition 37. In order to prevent the return of the coin when it is translated by the coin finger, the face of the partition is slotted to form the bent-in tongue 43, clearly illustrated in Figure 7 where the 30 front partition 40 is shown as partly broken away. At the base the runway is formed with an opening 44 so that the coin can escape into the bank proper.

The partition 37 as arranged entirely encloses the coin control mechanism for the 35 time piece and isolates it from the coin holding portion of the casing. To this end the partition is notched as at 45 to snugly fit about the upper portion of the cradle 7. The 40 partition is slotted at one side as at 46 to permit the locking spring 26 to pass freely therethrough and is likewise slotted as at 47 to permit the end of the slide to reciprocate freely therethrough as the time piece 45 is oscillated. Any desired spring arrangement may be used for quickly returning the time piece to normal upright position after winding. To this end the spring 48 is made fast at one end to the partition 37 and 50 at the other end to any portion of the oscillatable time piece cradle 7 or the slide 30.

In the operation of the device, on insertion of a coin, the auxiliary head 22 which 55 constitutes not only a winding element but also the means for positively translating the coin to check controlling position, is manually pushed to one side and the coin resting in the coin finger 29 is carried past the detent 43. During this operation the winding arbor is still held from rotation 60 since the slot 28 of the locking finger engages the squared portion 19 of the winding arbor. However, as soon as the coin is carried by the toe 29 under finger 26 the finger 65 is raised so that the slot 28 now surrounds

the round portion 23 of the winding arbor and the latter is now free to be wound. On release of the winding head it is snapped back into upright position by spring 48 and the locking finger 26 springs back onto the 70 squared portion 19 of the winding shaft to relock it. In case the winding arbor happens to lie diagonally to the slot 28, thereby hindering the free downward movement of spring 26, the minute the locking head 22 is 75 rotated the slightest bit the spring finger 26 will snap over the squared head and lock the same from further rotation and the stripper tongue 43 prevents return of the coin with the coin toe.

One of the advantages of this present construction of an oscillatable time piece resides in the fact that while the dial or face of the watch moves relatively to the casing it does not shift out of the opening in the 80 casing and constantly maintains its true bearing therein. At the same time if the user attempts in any way to detain the winding stem 22 in winding position, the dial of the time piece will be correspondingly shifted and is conspicuously in a non-readable position thereby impairing the utility of the time piece while in such position. It is manifest that various modifications of the generic invention are contemplated, and it is 85 not intended to limit the invention to the precise embodiment illustrated except in so far as is restricted by the scope of the appended claims as interpreted by the prior art.

What we claim as new and desire to secure by Letters Patent is:

1. A bank comprising an enclosing casing forming a money receptacle, a time piece, 105 means for shiftably mounting said time piece in said casing, and means for permitting the winding of said time piece only on shifting of the same.

2. A bank comprising an enclosing casing forming a money receptacle, a time piece, 110 shiftably mounted therein and arranged with its winding stem normally incapable of being wound and coin controlled means adapted to permit the winding of said stem on the shifting of said time piece.

3. A bank comprising an enclosing casing forming a money receptacle, a time piece, means for shiftably mounting said time piece in said casing with its dial visible and its winding arbor normally incapable of being wound, and coin controlled means for permitting the winding of said arbor on movement of said time piece, said time piece having its dial wholly visible during such shifting movement.

4. In a device of the class described, the combination of an enclosing casing, a time piece oscillatably mounted therein, means for locking the winding arbor of said time piece from rotation and coin controlled 120

- means for releasing said locking means on shifting of said time piece.
5. In a device of the class described, the combination of an enclosing casing, a stem-set, stem-wound watch having the usual knurled winding and setting head mounted wholly within said casing, a substantially duplicate winding head secured to the winding head of said watch and projecting through an aperture in said casing to permit said watch to be wound, a locking part on said duplicate winding head, and coin-controlled means in said casing cooperating with said locking part.
- 10 6. In a device of the class described, the combination of an enclosing casing, a stem-wound, stem-set, time piece provided with the usual knurled winding head mounted wholly within said casing, a false or auxiliary knurled winding head projecting through said casing so as to simulate the first-mentioned winding head, and coin-controlled means adapted to permit the winding of said watch by means of said false winding head.
- 15 7. In a device of the class described, the combination of an enclosing casing, a standard stem-wound time piece shiftably mounted therein, a windable extension detachably secured to the winding head of said time piece and projecting through said casing, means for locking said extension from rotation and coin controlled means for releasing said locking means on shifting of said time piece.
- 20 8. In a device of the class described, the combination of an enclosing casing, a stem-wound and stem-set watch therein having a winding and setting member projecting through said casing and constantly accessible to be grasped for winding, said windable member having a locking portion located thereon within the casing, shiftable means within said casing adapted to engage said locking portion to hold the same from rotation, and coin-controlled means for operating said shiftable means, said locking portion and shiftable means being constructed and arranged to permit the setting of said watch independently of the coin-controlled means.
- 25 9. In a device of the class described, the combination of an enclosing casing, a stem wound, stem-set, time piece therein having a windable member projecting through said casing and constantly accessible to be grasped for winding, means for locking said windable member from rotation and coin controlled means for releasing said locking means.
- 30 10. In a device of the class described, the combination of an enclosing casing, a time piece oscillatably mounted therein with winding and setting means projecting through said casing, means for locking said winding means from rotation and coin controlled means for releasing said locking means on oscillation of said time piece.
- 35 11. In a device of the class described the combination of an enclosing casing, a time piece shiftably mounted therein, and coin controlled means for permitting the winding of said time piece only on a predetermined movement thereof.
- 40 12. In a device of the class described, the combination of an enclosing casing, a stem-wound, stem-set watch mounted in said casing with a knurled winding and setting head projecting outside of said casing in an ever accessible position to be grasped for winding and setting, coin-controlled means located within said casing and cooperating with the winding and setting member of said watch for preventing the winding thereof, said means being constructed and arranged to permit the setting of said watch independently of the coin-control therefor.
- 45 13. In a device of the class described, the combination of an enclosing casing, a stem-wound, stem-set time piece provided with the usual knurled winding head mounted wholly within said casing, a false or auxiliary knurled winding head projecting through said casing so as to simulate the first-mentioned winding head, means forming a detachable driving connection between said usual and false winding heads, and coin-controlled means for locking said driving connection from rotation.
- 50 14. In a device of the class described, the combination of an enclosing casing, a standard stem-wound watch, means for detachably mounting said watch wholly within said casing, an auxiliary winding head disposed outside of said casing, means forming a splined driving connection between said auxiliary head and said watch stem head so as to permit the facile removal of said watch, and coin-controlled means for preventing the rotation of said driving connection.
- 55 15. In a device of the class described, the combination of an enclosing casing, a time-piece mounted therein provided with a rotatable member, a turning head on said member constructed and arranged to freely project from said casing in ever accessible position to be grasped for winding, said member being further constructed and arranged to have a limited longitudinal movement for setting the time-piece, a locking member on said rotatable and longitudinally shiftable member, and coin-controlled means constructed and arranged to cooperate with said locking member to hold the same from winding.
- 60 16. In a device of the class described, the combination of an enclosing casing, a time-piece mounted therein provided with a ro-

rotatable member projecting through said casing so as to be ever freely accessible for winding, said member being constructed and arranged to have a limited longitudinal movement for setting the time-piece, coin-controlled means for locking said rotatable member from winding, said means being

constructed and arranged to release said rotatable member when the latter is in hand setting position.

10

In testimony whereof, we affix our signatures.

JAMES BALLARD MOORE.

GEORGE DOMINIC GALLAGHER.
